UNITED STATES PATENT OFFICE.

WILSON H. HENNE AND GUY TIPPIN, OF DEFIANCE, OHIO.

THILL-COUPING.

SPECIFICATION forming part of Letters Patent No. 370,785, dated October 4, 1887.

Application filed June 24, 1887. Serial No. 242,415. (No model.)

To all whom it may concern:

Be it known that we, WILSON H. HENNE and GUY TIPPIN, citizens of the United States, residing at Defiance, in the county of Defiance 5 and State of Ohio, have invented certain new and useful Improvements in Thill-Couplings, of which the following is a specification, to wit:

This invention relates to an improvement in thill-couplings; and it consists in certain 10 peculiarities of the construction and arrangement of the same, substantially as will be hereinafter more fully set forth and claimed.

In order to enable others skilled in the art 15 to which our invention pertains to make and use the same, we will now proceed to describe its construction and operation, referring to the accompanying drawings, in which—

Figure 1 is a side elevation of our coupling applied to an axle; and Fig. 2 is a perspective 20 view of our device with the various parts separated, but in such relation to each other as to render their proper connection readily understood.

a represents the usual clip for surrounding 25 the axle, which is in the present instance formed or provided with a single stationary lug or ear, *a'*, projecting out in front in the ordinary way. This clip is also formed with a horizontal groove or socket, *a''*, which receives an arm, *b*, upon which is carried the 30 second ear, *b'*, as will be clearly seen in Fig. 2.

The thill *c* is formed, as is usual, with an

eye, *c'*, which is placed between the ears *a' b'* and secured by a bolt, *d*, passed through both ears and the thill-eye, a small washer, *e*, of 35 rubber, felt, paper, or other elastic material, being passed over the bolt between each ear and the eye to prevent rattling.

It will be at once understood that the ears *a' b'* may be separated and pressed together to 40 fit a thill-eye of any length and to accommodate washers of any suitable thickness, while the construction renders the coupling as strong as in ordinary cases where both ears are rigidly secured upon the clip. The shape of the 45 arm *b* and its receiving-socket is not material, and we will form it half-round, dovetailed, rectangular, or in any other shape deemed best or found most desirable.

Having thus fully described our invention, 50 what we claim as new, and desire to secure by Letters Patent, is—

The combination, with the clip *a*, provided with a rigid ear, *a'*, and socket *a''*, of the sliding arm *b*, its ear *b'*, and bolt *d*, substantially 55 as and for the purpose set forth.

In testimony whereof we affix our signatures in presence of two witnesses.

WILSON H. HENNE.
GUY TIPPIN.
